RELAY

Laurence E. Gardiner, Stratford, N. J.

Application December 24, 1940, Serial No. 371,560

12 Claims. (Cl. 200—104)

This invention relates to relays and more particularly to a relay which will have a high degree of sensitivity.

It is an object of the present invention to provide an improved relay embodying simplicity in its construction while maintaining reliability under operating conditions.

It is a further object of the present invention to provide an improved multiple contact relay which will be highly sensitive and capable of operation at high speed.

It is a further object of the present invention to provide an improved relay which is capable of adjustment at the time of assembly and which will remain in adjusted condition.

It is a further object of the present invention to provide an improved relay which will be suitably encased and adequately protected from external dust and dirt and from moisture.

It is a further object of the present invention to provide a relay which will be comparatively free from sparking at the contacts.

It is also an object of the present invention to provide an improved form of contactor mounting.

Other objects of the invention will appear from the annexed specification and claims.

The nature and characteristic features of the invention will be more readily understood from the following description, taken in connection with the accompanying drawing forming part hereof, in which:

Fig. 1 is a vertical central sectional view, considerably enlarged, of a preferred embodiment of a relay made in accordance with the present invention;

Fig. 2 is a horizontal sectional view taken approximately on the line 2—2 of Fig. 1;

Fig. 3 is a fragmentary central sectional view taken approximately on the line 3—3 of Fig. 1; and

Fig. 4 is a bottom plan view of the relay shown in Fig. 1.

It will, of course, be understood that the description and drawing herein are illustrative merely, and that various modifications and changes may be made in the structure disclosed without departing from the spirit of the invention.

Referring more particularly to the drawing, in which a preferred embodiment of the invention is illustrated, an outer cylindrical casing 10 is provided, of suitable insulating and waterproof material such as Bakelite, hard rubber or any desired synthetic plastic material.

The upper end of the casing 10 is closed by a

suitable cap 11 of the same material as the casing 10, the cap 11 preferably being permanently secured to the casing for the purpose of preventing access to the interior of the casing 10 after the relay has been assembled.

The lower end of the casing 10 is preferably closed by a suitable base portion 12 which is also preferably of the same material or a material similar to that of the casing 10. The base portion 12 may, if desired, have an outwardly extending ledge 13 to provide an abutment for the lower edge of the casing 10 in the sealed position of the casing 10 on the base portion 12. The casing 10 preferably fits the base portion 12 above the ledge 13 in such a manner that the interior is enclosed and access of dirt or dust and moisture to the interior of the relay is prevented.

The base portion 12 is preferably provided with a plurality of contact prongs, the contact prongs 14 and 15 being provided for input to the winding or coil 16, as hereinafter more fully referred to. The contact prongs 17 and 18 are connected to movable contact members and the contact prongs 19, 20, 21 and 22 to fixed contact members, as hereinafter more fully pointed out. The base portion 12 is also preferably provided with a projection 23 of the same material as the casing 10 with a suitable indexing portion 24 thereon for locating the respective contact prongs of the relay at the proper locations in the socket or other mounting for the relay.

Within the casing 10 a central vertical tube 25 is provided, of suitable insulating material such as Bakelite, hard rubber or other desired synthetic plastic material. The tube 25 has mounted thereon, a short distance inwardly from the upper and lower ends thereof, suitable disks 26 and 27 of similar insulating material, and the winding 16, comprising a suitable number of turns of wire, is provided on the tube 25 and between the disks 26 and 27.

The winding 16 in the preferred embodiment of the invention may be of any desired impedance to match the particular circuit in which the relay is employed. The relay is particularly adapted for use in signal equipment, alarm systems, and detecting systems of various sorts. It will, of course, be understood that for the various uses the impedance of the winding 16, the number of turns thereof, and other electrical, magnetic and mechanical characteristics thereof may be very widely varied.

Conductors 28 and 29 connected to the ends of the winding 16 are in turn respectively connected to the contact prongs 14 and 15. The

coil input circuit thus comprises the input contact prongs 14 and 15, the conductors 28 and 29 and the winding 16.

The winding 16 is also preferably enclosed within a metallic casing or sheath of magnetizable material and the metallic casing preferably includes suitable metallic end disks 30 and 31 of magnetizable material which are respectively mounted above and below the winding. A cylindrical casing portion 32 of magnetizable material is also provided and extends between and is soldered or otherwise secured to the end disks 30 and 31. The metal casing forms a part of the magnetic circuit of the relay and thus reduces the reluctance of that circuit while also serving as a shield to diminish interference with external circuits. The metal casing may, if desired, be grounded in any preferred manner.

An insulating covering 33 is provided and around this an insulating wrapping 34 is provided, the wrapping 34 being held in position in any desired manner.

A metallic core member 35 is provided and also forms a part of the magnetic circuit. The core member 35, preferably composed of a round pin of magnetizable material, is mounted with a snug fit within the lower portion of the tube 25. The core member 35 is of a length such that the lower end thereof extends below the disk 27 but does not extend to the lower end of the tube 25. The core member 35 may be moved within the tube 25 to the desired position of adjustment.

An armature 36 is also provided, the armature 36 being of a suitable material responsive to magnetic force and is preferably in the form of a round pin of an external diameter less than the internal diameter of the tube 25. The armature 36 is freely movable vertically in the upper portion of the tube 25, as hereinafter more fully referred to. The lower end of the armature 36 may have a stop pin 37 of non-magnetic material mounted thereon to serve as a stop or spacer between the armature 36 and the core member 35. The core member 35 is adjusted so that the space between the pin 37 and the upper end of the core member 35 will permit of adequate and proper movement of the armature 36. Upon energization of the winding 16 the armature 36 will be moved so that the stop pin 37 is brought into contact with the core member 35.

The armature 36 has secured to the upper end thereof a disk 40 of Bakelite or similar material for purposes hereinafter more fully referred to.

A covering disk 41 of Bakelite or similar material is provided above the end disk 30.

Contact supporting brackets 45 and 46 are provided for carrying contact disks 45^a and 46^a of tungsten or other desired material. These brackets 45 and 46 preferably are made of thin flat strips of spring brass so that they may be bent if necessary to the desired position of adjustment. The brackets each include a horizontally disposed portion 45^b and 46^b and a vertically disposed portion 45^c and 46^c, the vertically disposed portions 45^c and 46^c extending down alongside the casing 10 and preferably between the covering 33 and the wrapping 34 to provide the desired electrical insulation. The contact brackets 45 and 46 are connected respectively to the contact prongs 22 and 19 carried by the base portion 12.

Interior contact brackets 47 and 48 are also provided and are also preferably made of thin flat strips of spring brass so that they may be bent to the desired position of adjustment. The brackets 47 and 48 each have contact disks 47^a

and 48^a similar to the other contact disks and also have horizontal and angularly disposed portions 47^b and 48^b with the contact disk portions 47^a and 48^a secured at the ends thereof. These contact brackets 47 and 48 hold the contacts 47^a and 48^a mounted thereon in substantially fixed portion. The contact brackets 47 and 48 also have vertically disposed portions 47^c and 48^c which extend downwardly along the casing 10, preferably between the covering 33 and the wrapping 34, are insulated from the metallic casing 32 and from each other and are connected, respectively, to contact prongs 20 and 21 carried by the base portion 12.

Movable contact members 50 and 51 operable by the movement 36 of the armature are also provided, preferably of thin flat strips of spring brass and have portions which extend vertically downward along the outside of the casing 32 between the covering 33 and the wrapping 34 and are electrically insulated. The movable contact members 50 and 51 are connected, respectively, to contact prongs 17 and 18 by downwardly extending strips 50' and 51' disposed between the covering 33 and the wrapping 34. These contact brackets 50 and 51 each have generally horizontally disposed portions 50^a and 51^a which extend inwardly and under the disk 40 and are bent back as at 50^b and 51^b along the portions 50^a and 51^a for a part of the length thereof and extend upwardly as at 50^c and 51^c. The movable contact brackets have, mounted at the upper ends thereof, opposed face contact portions 50^d and 51^d for contact, respectively, with the contact face portions 47^a and 48^a carried by the inner contact brackets 47 and 48 and the contact face portions 46^a and 45^a carried by the outer contact brackets 46 and 45.

It will be noted that the upwardly extending portions 50^c and 51^c are greater in length than the horizontally extending portion 50^a and 51^a so that a multiplying action is obtained when the armature 36 and the disk 40 carried thereby move downwardly and carry with them the inner end portions of the movable contact mountings 50 and 51.

A brass strip 52 is provided which extends downwardly a sufficient distance between the covering 33 and the wrapping 34 to provide for anchoring, the upper end extending transversely to a location to provide a stop or limit for the upward movement of the armature 36.

The operation will be briefly summarized. The relay is shown in its deenergized position in Figs. 1 and 2 and the armature 36 is in its normal upper position. An electrical circuit is provided which includes the contact prong 17, the strip 50', the contact member 50 with its contact face portion 50^d in contact with the contact face portion 47^a, the contact strip 46^c and the contact prong 19. A similar circuit is also provided which includes the contact prong 18, the contact strip 51', the contact member 51 with its contact face portion 51^d in contact with the contact face 48^a of the contact member 45, the contact strip 45^c and the prong 22.

When the coil is energized through the circuit which includes the contact prong 14, the conductor 28, the winding 16, the conductor 29 and the contact prong 15, a magnetic circuit is set up which tends to draw the armature 36 downwardly. The magnetic circuit includes the winding 16, the core member 35, the metallic casing with its cylindrical portion 32 and end disks 30 and 31, and the armature 36. Upon the down-

ward movement of the armature 36, the force applied from the armature 36 to the disk 40 is applied to the inwardly extending end portions of the spring contact members 50 and 51. The downward movement causes the contact members 50 and 51 to be actuated so that the contact portions 50^a and 51^a are first moved out of their initial position in engagement with the contact members 45 and 46 and upon further continued downward armature movement the contact members 50 and 51 are moved so that their other contact face portions 50^b and 51^b are then brought into contact with the contact members 48 and 49. Two new electrical circuits are thus set up. One of these circuits includes the prong 17, the contact strip 50', the contact member 50 with its contact face portion 50^a in contact with the contact face portion 47^a, the contact strip 47^c and the prong 20. The other circuit includes the prong 18, the contact strip 51', the contact member 51 with its contact face portion 51^a in contact with the contact face portion 48^a, the contact strip 48^c and the prong 21.

Upon deenergization of the winding 16, the armature 36 is released so that it tends to move upwardly and permit the contact members 50 and 51 to return to their initial positions. The spring action of the movable contact members 50 and 51 aids the upward movement of the armature 36.

The making and breaking of the contacts may occur very rapidly. The closeness of the core and the armature and the particular arrangement of the magnetic circuit provides for an increased magnetic field and thus increases the sensitivity for a given power input. The small motion of the armature and the disposition of the armature provide for retention of the armature within the magnetic zone of greatest strength. The character of the action of the movable contact members which are provided and the multiplication of the motion of the armature provide for a very rapid making and breaking of the contacts.

The manner of mounting the contact face portions 45^a, 46^a, 47^a and 48^a permits of sufficient rigidity to obtain a good contact and also sufficient elasticity to prevent any undesired rebound of the movable contact members.

I claim:

1. A relay having a winding, an armature movable with respect to said winding, a contact member mounted beyond one end of said winding, and a movable contact member fixedly supported at one end, said movable contact member having a spring arm portion for engagement by said armature and a contact supporting arm portion extending angularly from said spring arm portion, said supporting arm portion having a contact portion movable into and out of contact with said first-mentioned contact member.

2. A relay having a winding, an armature movable with respect to said winding, a contact member mounted beyond one end of said winding, and a movable contact member fixedly supported at one end, said movable contact member having a spring arm portion for engagement by said armature and a contact supporting arm portion extending angularly from said spring arm portion, said supporting arm portion having a contact portion movable into and out of contact with said first-mentioned contact member and being of greater length than said spring arm portion for multiplying the effect of the movement of the armature.

3. A relay having a winding, an armature movable with respect to said winding, spaced contact members mounted beyond one end of said winding, and a movable contact member having a cantilever spring arm portion for engagement with said armature and a contact supporting arm portion extending angularly from said spring arm portion, said supporting arm portion having a contact portion movable between said spaced contact members for alternate contact therewith.

4. A relay having a winding, an armature movable with respect to said winding, spaced contact members mounted beyond one end of said winding, and a movable contact member having a cantilever spring arm portion and a contact supporting arm portion extending angularly from said spring arm portion, said supporting arm portion having a contact portion movable between said spaced contact members for alternate contact therewith and being of greater length than said spring arm portion for multiplying the effect of the movement of the armature.

5. A relay having a winding, an armature movable with respect to said winding, spaced contact members mounted beyond one end of said winding, a movable contact member having a spring arm portion radially disposed at the end of said winding for engagement with said armature, said movable contact member also having an integral contact supporting arm portion extending angularly from said spring arm portion, and contacts carried by said supporting arm portion and movable between said spaced contact members for alternate contact therewith.

6. A relay including a magnetic circuit and having a winding, an axially movable armature actuated by said magnetic circuit, spaced contact members mounted beyond one end of said winding and in a horizontal plane out of alignment with the path of movement of said armature, a resilient movable contact member having a spring arm portion for engagement with said armature, said movable contact member also having a contact supporting arm portion extending angularly from said spring arm portion, and contacts carried by said supporting arm portion and movable between said spaced contact members for alternate contact therewith.

7. A relay including a magnetic circuit and having a winding, an axially movable armature actuated in one direction by said magnetic circuit, a resilient movable contact member having a spring arm portion for engagement with said armature and for actuation of said armature in the opposite direction, said movable contact member also having a contact supporting arm portion extending at an angle from said spring arm portion, spaced contact members mounted beyond one end of said winding and in a horizontal plane out of alignment with the path of movement of said armature, and contacts carried by said supporting arm portion and movable between said spaced contact members for alternate contact therewith.

8. A relay including a magnetic circuit and having a winding, an armature movable axially with respect to said winding and actuated in one direction by said magnetic circuit, a movable contact member having a cantilever spring arm portion radially disposed at the end of said winding for engagement with said armature and for actuating said armature in the opposite direction, said movable contact member also having

a contact supporting arm portion extending at an angle from said spring arm portion, spaced contact members mounted beyond one end of said winding, and contacts carried by said supporting arm portion and movable between said spaced contact members for alternate contact therewith, said supporting arm portion being of greater length than said spring arm portion for multiplying the effect of the movement of the armature.

9. A relay having a winding, an armature movable with respect to said winding, a contact member mounted beyond one end of said winding, a movable contact member mounted on said winding, said movable contact member including a cantilever spring arm portion extending toward said armature for engagement therewith and a portion extending along said spring arm portion and at an angle away from said spring arm portion to provide a contact supporting arm portion, and a contact carried by said supporting arm portion and movable into and out of contact with said first-mentioned contact member.

10. A relay having a winding, an armature movable with respect to said winding, a contact member mounted beyond one end of said winding, a movable contact member mounted on said winding, said movable contact member including a cantilever spring arm portion extending toward said armature for engagement therewith and a portion extending along said spring arm portion and at an angle away from said spring arm portion to provide a contact supporting arm portion, and a contact carried by said supporting

arm portion and movable into and out of contact with said first-mentioned contact member, said supporting arm portion being of greater length than said spring arm portion for multiplying the effect of the movement of said armature.

11. A relay having a winding, an armature movable with respect to said winding, a pair of spaced contact members mounted beyond one end of said winding, a movable contact member mounted on said winding, said movable contact member including a cantilever spring arm portion extending toward said armature for engagement therewith and a portion extending along said spring arm portion and at an angle away from said spring arm portion to provide a contact supporting arm portion, and contacts carried by said supporting arm portion and movable between said spaced contact members for alternate contact therewith.

12. A relay having a winding, an armature movable with respect to said winding and having an enlarged end portion, a contact member, a movable contact member, said movable contact member including a cantilever spring arm portion extending toward said armature for engagement with the enlarged end portion thereof and a portion extending back along said spring arm portion and at an angle away from said spring arm portion to provide a contact supporting arm portion, and a contact carried by said supporting arm portion and movable into and out of contact with said first-mentioned contact member.

LAURANCE E. GARDINER.
